Patented Sept. 12, 1916.

UNITED STATES PATENT OFFICE.

FREDERICK A. W. GRIESAU, OF ALBANY, NEW YORK.

LOCK.

1,198,025.

Specification of Letters Patent. Patented Sept. 12, 1916.

Application filed March 18, 1916. Serial No. 85,061.

To all whom it may concern:

Be it known that I, FREDERICK A. W. GRIESAU, a citizen of the United States of America, residing at the city of Albany, in the county of Albany and State of New York, have invented certain new and useful Improvements in Locks, of which the following is a specification.

My invention relates to locks, and the object of my invention is to provide a lock adapted to prevent the rotation of the wheel of an automobile; together with such elements and combinations as are hereinafter more particularly set forth and claimed. I accomplish these objects by means of the mechanism illustrated in the accompanying drawing, in which:

Figure 1 is a plan. Fig. 2 is a section along the lines, 1—1, on Fig. 1. Fig. 3 is an enlarged sectional view, with parts broken away, of the lock proper. Fig. 4 is a section along the lines, 1—1, on Fig. 3.

Similar letters refer to similar parts throughout the several views.

To the axle frame, A, I secure a plate, a, in connection with which I mount a plate, B, supported thereon by the braces, b, or in any suitable manner. The plate, B, is provided with a series of openings, C, therethrough adapted to receive the head, D, of the plunger. There are one or more openings, d, in the spokes of the wheel which will register with the openings, C, in the plate, B. In one of the openings, d, in the spokes, I place the barrel, E, of the lock. Within the barrel, E, I arrange a compressible plunger provided with a head, D, a spiral spring, F, a plate, f, and a bar, G. Projecting into the barrel, G, is an annular shoulder, h.

The bar, G, may be pressed into the barrel, E, which will cause the spiral spring, F, to be pushed out and the head, D, of the plunger to enter one of the openings, C, provided the opening, C, is in register therewith; if not, the pressure on the end of the bar, G, will cause the spring, F, of the plunger, which cannot be forced forward, it resting against the plate, B, to become contracted. But if the wheel is moved so as to bring the opening, C, in register with the head of the plunger, the plunger, under the influence of the contracted spring, will enter the opening, C, and thus lock the wheel.

Within the bar, G, I pivot the trigger, J, which has on one side a cam-shaped formation engaging with the cutaway portion of

the bar, G, which is so arranged that when the bar is pressed inward acting on the spring, F, the trigger, J, will be moved forward and the catch, K, under the influence 60 of the spring, H, pressing against the heel, j, of the trigger, will come in contact with the annular shoulder, h, which will prevent the head, D, of the plunger from being moved after the spring, F, has acted upon 65 it; because the plate, f, has been moved forward and the end of the trigger, J, presses against it and the catch, K, of the trigger being held by the annular shoulder, h, it is apparent that the plunger cannot be removed from the opening, C, until the catch 70 has been liberated.

Around the bar, G, and within the barrel, E, I place the spring, H, which is seated against the shoulder, h, against the heel, j, 75 of the trigger, and against the shoulder, g, on the bar, G. One function of the spring, H, is to force the bar and therefore the plunger out of the barrel when the catch, K, is liberated.

For the purpose of unlocking the wheel, I place in the barrel, E, the cam-shaped plate, M, rotated by means of the key, L, which when rotated will strike against the heel, j, of the trigger, J, and press the catch, 85 K, out of connection with the shoulder, h, which will immediately relieve the spring, H, causing the bar and the plunger to be forced backward into the barrel.

What I claim as my invention and desire 90 to secure by Letters Patent is:

1. A lock adapted to be used in connection with an automobile, comprising a plate secured to the axle frame; a series of openings through said plate; a lock inserted 95 through one of the spokes of the wheel comprising a barrel; a compressible plunger therein, said plunger adapted to be inserted in one of said openings in said plate; means for locking said plunger with its 100 head inserted in said plate; with means for releasing the locking means aforesaid; and means for withdrawing said plunger head when said locking means has been released.

2. A lock adapted to be used in connection 105 with an automobile, comprising a plate provided with a series of openings therethrough secured to the axle frame of an automobile; a lock set in one of the spokes of the wheel comprising a barrel; a plunger; a spring 110 connected with said plunger seated against the end of the plunger and also against a

shoulder on said barrel; a trigger connected with the plunger within said barrel, said trigger so formed that when the plunger is so acted upon as to project its head into one of the openings of the plate said trigger will, when the plunger has entered the plate, become locked by engaging said shoulder on said barrel; a spring resting against said shoulder and against the plunger whereby, when the trigger has been released, the plunger will be forced out of connection with the plate; and means for releasing said trigger when desired.

3. A lock adapted to be used in connection with an automobile, comprising a plate pro-

vided with a series of openings therethrough secured to the axle frame; a barrel adapted to be inserted through one of the spokes of the wheel; a resilient plunger placed in said barrel; a spring in the plunger; means in the plunger for holding it, when projected, in its projected position; with means for releasing the holding means when desired. 20 25

In testimony whereof I have affixed my signature in presence of two witnesses.

FREDERICK A. W. GRIESAU.

Witnesses:

FREDERICK W. CAMERON,
BEULAH CARLE.
